UNITED STATES PATENT OFFICE.

FRITZ REHM, OF LICHTENFELS, AND KARL WINDSTOSSEN, OF NUEREMBERG,
GERMANY.

TELESCOPE FOR SUBMARINE BOATS.

No. 850,054.

Specification of Letters Patent.

Patented April 9, 1907.

Application filed November 4, 1905. Serial No. 285,852.

To all whom it may concern:

Be it known that we, FRITZ REHM, a citizen of the Empire of Germany, residing at Lichtenfels, in the Empire of Germany, and 5 KARL WINDSTOSSEN, a citizen of the Empire of Germany, residing at Nuremberg, in the Empire of Germany, have invented a new and useful Telescope for Submarine Boats, of which the following is a specification.

10 In submarine boats hitherto telescopes were in use, by means of which it was possible to keep a lookout while the boat was beneath the level of the sea. However, it was necessary to move about the lower end of the 15 telescope within the boat in order to inspect different parts of the horizon or sea, which of course is a great drawback.

Our invention relates to a telescope for submarine boats by means of which the several fields of view representing several parts of the horizon or sea are obtained within one and the same circle, the several fields of view being preferably so arranged that the field of view of the fore part of the horizon or sea is 25 made the chief field and larger than the other fields of view. Evidently it is of great importance to render the chief field as large as possible—in other words, to render the horizon within the chief field complete—as it is 30 chiefly the horizon which requires to be watched and not the sky or the lower part of the view. For this reason we utilize either the front part alone or the front and rear parts of the area of the circle for the arrangement of the subsidiary fields of view, which 35 represent parts of the horizon to starboard, port, and astern, also intermediate parts, if so preferred. We may even increase the number of the subsidiary fields of view in order to 40 be able to inspect the entire horizon all round at a time. Then the commander or conductor of the boat need not change his place, while he is able to watch everything. Of course the scale of the subsidiary pictures 45 will be necessarily smaller than that of the chief picture.

We further so arrange the telescope that all the pictures in the subsidiary fields of view are erect in opposition to other known 50 telescopes where the subsidiary pictures are turned through an angle increasing from zero to one hundred and eighty degrees when

counting from the fore to astern. The several subsidiary pictures are distinguished one from the other by different colors, either 55 wholly or partly, or they may be marked by suitable signatures. The commander or conductor will then be able not only to see everything as it is, but also to know which part of the horizon the respective subsidiary picture represents.

We will now proceed to describe our invention with reference to the accompanying drawings, in which—

Figure 1 is a longitudinal section through 65 a telescope for submarine boats. Fig. 2 is a longitudinal section through a modified telescope. Figs. 3 to 6 represent different arrangements of the chief and the subsidiary fields of view within a circle. Figs. 7 to 9 show 70 the corresponding diagrams to show which parts of the horizon the several fields of view represent. Fig. 10 is a longitudinal section through the upper end of a telescope with four objectives. Fig. 11 is a horizontal section 75 through the line x , y in Fig. 10, and Figs. 12 to 15 represent various diaphragms. Figs. 16 to 20 represent, on a larger scale, prisms of the subsidiary objectives provided with means adapted to produce a distinction or designation in the several subsidiary fields of view. Fig. 21 is a vertical 80 sectional elevation of a modification of the telescope. Fig. 22 is a horizontal cross-section of the device shown in Fig. 21, wherein 85 several diaphragms are not shown. Figs. 23 to 25 are plane views of the diaphragms, and Fig. 26 is a diagram of the various sectors of the horizon within the fields of view of the objectives.

Similar letters of reference refer to similar parts throughout the several views.

R denotes a telescope, which may have a shape as shown in Fig. 1 or in Fig. 2, it being desirable to contract its upper part in order 95 to render it as much as possible invisible. The upper end of the telescope is provided with several openings 1 2 3 4, either in the same cross-plane or in different cross-planes, as in Fig. 10, for receiving the objectives. 100 Preferably these openings 1 2 3 4 are made conical in order to obtain as large optic angles as possible, as is indicated by dotted lines in Figs. 1, 2, 10, and 11. The lower end

of the telescope R is provided with a single ocular, which produces the pictures within a circle 5. (See Figs. 3 to 6.)

When assuming the telescope to be provided with four objectives at ninety degrees from each other and having optic angles, as indicated in Fig. 7, we so arrange the telescope that the chief field of view nearly occupies the whole area of the circle 5 in Fig. 3, with the exception of the upper part divided by the secant 6. Within the upper part of the area of the circle 5 three fields of view 7, 8, and 9 are disposed, which represent parts of the horizon to port, astern, and starboard, respectively, and may be differently colored in correspondence with the similarly-hatched sectors in the diagram in Fig. 7, (taken to be in a horizontal plane.) It will be seen that four angles α are left between the four optic angles, which means that only four different parts of the horizon and not the entire horizon can be viewed at a time. In order to be able to examine the parts of the horizon within the angles α , it will be necessary to turn the telescope through an angle of $\frac{1}{2} \alpha$ in either direction.

The telescope may have five objectives at equal angles from each other, as is shown in the diagram Fig. 8, when the angles α will be smaller than before. The four subsidiary fields of view 7 to 10 may be arranged in the upper part of the circle 5, which is divided from the chief field of view by a broken line 11. These four subsidiary fields of view 7 to 10 are shown as colored, but only in a small circle each.

The telescope may also have more objectives, so as to comprise the entire horizon, as is indicated in Fig. 9, where it is supposed to have eight objectives. The seven subsidiary fields of view 7 to 14 may be arranged in the top and bottom parts of the area of the circle 5, either as in Fig. 5 or as in Fig. 6. They are shown in Fig. 5 as marked with letters corresponding to those in the diagram Fig. 9, which designation may also be employed in Fig. 6.

Fig. 10 shows the arrangement of the chief system for collecting all the rays of light from the fore part of the horizon and sending them downward through the telescope R. It comprises a lens 15 as an objective, a prism 16, and a lens 17, all of which may be secured in any known manner. A diaphragm 18 (shown at Fig. 12 and having a single aperture 19 of a shape similar to that of the chief field of view in Fig. 4) is disposed immediately beneath the lens 17 and serves for permitting only those rays of light to pass downward which are to produce the chief picture in the chief field of view. These rays of light pass through a system of lenses 20, 21, and 22 of any known construction to the system at the lower end of the telescope, which will be referred to later on.

Beneath the diaphragm 18 a subsidiary system is disposed in the telescope R for collecting all the rays of light from astern through the opening 2 and sending them downward in a beam of rays separate from the chief beam of rays. This system is shown as comprising a lens 23 as an objective and two prisms 24 and 25, between which a second diaphragm 26 is disposed. This diaphragm is shown at Fig. 13 and has two small apertures 27 and 28 in addition to the large aperture 19, as in Fig. 12. From Fig. 11 it will be seen that the opening 2 is placed eccentrically, so that the rays of light collected by the objective 23 and deflected by the two prisms 24 and 25 may pass first through the aperture 27 upward and then through the aperture 28 downward, the aperture 28 corresponding to the subsidiary field of view 8 in Fig. 3. Two other subsidiary systems are also disposed for collecting all the rays of light from port and starboard, respectively, and for sending them downward in two separate beams of rays to the lower system. The said two subsidiary systems comprise each a lens 29 in the conical opening 3 or 4, respectively, (see Fig. 11,) as a lateral objective and two prisms 30 and 31. Between the four prisms 30 30 31 31 a further diaphragm 32 (shown at Fig. 14) is disposed, which is provided with four apertures 33 33 and 34 34 in addition to the apertures 19 and 28, as in the preceding diaphragm 26. The rays of light collected by the objective 29 in either subsidiary system and deflected by the two prisms 30 and 31 pass first upward through the aperture 33 and afterward downward through the aperture 34. The two apertures 34 34 correspond to the two subsidiary fields of view 7 and 9, respectively, in Fig. 3. A fourth diaphragm 35 (shown at Fig. 15) may be disposed in the telescope R beneath the part shown at Fig. 10. It is evident that the several diaphragms 26, 32, and 35 serve for permitting only those rays of light to pass downward which produce the respective subsidiary pictures.

The modification shown in Figs. 21 to 25 in its general disposition is of the same construction as the telescope above described in connection with Fig. 10, except in that the lenses employed in the main and subsidiary objectives are negative, (instead of the positive lenses shown in Fig. 10,) such as the lenses 15^a and 17^a in the main objective and the system of lenses 23^a and 23^b, represented in the astern objective, and in that the diaphragms 26 and 32 are duplicated by diaphragms 26^a and 32^a, respectively, of identical construction.

The lens 20 in Fig. 1 serves for erecting the chief picture, while the lenses 36 36, in combination with the prisms 31 31 in Fig. 11, (turned through convenient angles in the

horizontal plane,) serve for erecting the subsidiary pictures. A separate lens 36 is disposed for each subsidiary objective system in the telescope represented in Fig. 1, in which 5 construction the beams of rays of light passing the main objective and the subsidiary objectives are separately projected downward within the tube R by convenient systems.

We do not further describe the said three 10 systems, as their construction is immaterial and it is well known how to arrange other systems for attaining the above-mentioned results. The prisms may also be replaced by mirrors or other known means. For example, in Fig. 2 the said prisms 31 31 are arranged for sending the separate beams of rays through the same lens 20 through which the chief beam of rays passes. Of course 15 these separate beams of rays will also pass through the second lens 21.

The prisms 25 and 31 are disposed in such a position that their planes of reflection are bisecting the angles a_1 , a_2 , a_3 , formed by the horizontal optical axis of the principal sector 20 and those of the subsidiary sectors, as shown in Figs. 22 and 26, so that if the aperture of the angle a_3 between the optical axes of the principal or fore sector and of the astern sector is of one hundred and eighty degrees 25 30 the plane of reflection of the prism 25 must be disposed at ninety degrees with respect to the axis of the principal system, and if the angles a_1 and a_2 , formed by the optical axes of the principal sector and of the port and starboard sectors, respectively, are of ninety degrees the plane of reflection of the prisms 31 must be disposed so as to include 35 an angle of forty-five degrees with the optical axis of the principal system. By this arrangement the images produced by the different systems are turned through an angle as will be required for erecting the objects with respect to the main picture.

At the lower end of the telescope R the 40 above-mentioned system, comprising a lens 37; as an ocular, and a prism 38, is disposed for deflecting the rays of light and forming the chief picture and the subsidiary pictures in the corresponding fields of view. The 45 construction of the lower system is equally immaterial and may be varied to suit the circumstances.

The main picture in the main field of view 50 serves for steering the submarine boat, while the subsidiary pictures in the subsidiary fields of view will enable the commander or conductor to simultaneously watch the remaining parts of the horizon without changing his place.

55 The telescope may consist of two tubes slidable the one within the other, such as shown in Fig. 2, so that its head part may be raised or lowered at will.

The ocular 37 may be of any known or

suitable construction and combined with any 65 other reflector instead of a prism 38.

In case differently-colored subsidiary pictures are to be produced suitable glass panes in the respective colors may be disposed within the system or the ocular. Preferably they are located above the prisms 24 and 30, as represented at 40 in Fig. 16, when it is desired to have the entire fields of view colored throughout, Fig. 3. A partial coloring of the subsidiary fields of view, Fig. 4, is 70 75 obtained by the employment of a small correspondingly-shaped piece 41 of colored glass or other transparent material situated at a convenient place above the prisms 24, Fig. 17.

In case the subsidiary pictures are to be 80 marked with signatures, Fig. 5, it is evident that corresponding signatures will have to be made on glass panes or lenses or prisms in the lower system or the ocular. They are conveniently placed above the upper surface of 85 the prisms 24 and 30, respectively, as represented at 42 in Figs. 18 to 20, and affixed thereto in any appropriate manner or made by etching, painting, photographing, or the like. 90

In case the telescope provided with four objectives does not comprise the entire horizon, as is indicated at Fig. 7, the telescope will require to be provided with an arm or other known means to enable the operator to turn 95 the telescope through an angle of $\frac{1}{2} \alpha$ and to examine the remaining parts of the horizon. In case the telescope is arranged to comprise the entire horizon, as indicated in Fig. 9, of course no arrangement for turning the telescope need be made. 100

In Figs. 3 to 6 the subsidiary fields of view are shown as circular; but it is evident that they can be given any other shape, as it is only necessary to provide the respective diaphragms 26, 32, and 35 (see Figs. 13 to 15) with apertures 28 34 34 of the desired shape, (square, rectangle, oval, &c.) 105

What we claim as our invention, and desire to secure by Letters Patent, is— 110

1. In a telescope for submarine boats, the combination with a barrel, of a main objective system adapted to produce a picture of a certain part of the horizon, a plurality of subsidiary objective systems adapted to produce smaller subsidiary pictures of other parts of the horizon, means for erecting the subsidiary pictures with respect to the main picture, means for projecting the various pictures downwardly within the barrel, and 115 an ocular system arranged for observing the pictures all at a time. 120

2. In a telescope for submarine boats, the combination with a barrel, of a main objective system capable of producing a picture of a certain part of the horizon, subsidiary objective systems capable of producing smaller subsidiary pictures of other parts of the hori- 125

zon, all objective systems being adapted to project the pictures downwardly within the barrel, means for erecting the subsidiary pictures with respect to the main picture, and 5 an ocular system arranged for observing the pictures all at a time.

3. In a telescope for submarine boats, the combination with a barrel, of a main objective system adapted to produce a picture of a 10 certain part of the horizon, a plurality of subsidiary objective systems adapted to produce smaller subsidiary pictures of other parts of the horizon, means for erecting the subsidiary pictures with respect to the main 15 picture, diaphragms within the barrel having apertures corresponding to the number, place, and shape of the pictures, means for projecting the various pictures downwardly within the barrel, and an ocular system ar- 20 ranged for observing the pictures all at a time.

4. In a telescope for submarine boats, the combination with a barrel, of a main objective system adapted to produce a picture of a 25 certain part of the horizon, a plurality of subsidiary objective systems adapted to produce smaller subsidiary pictures of other parts of the horizon, means for erecting the subsidiary pictures with respect to the main pic- 30 ture, means for differently marking the subsidiary pictures, means for projecting the various pictures downwardly within the barrel, and an ocular system arranged for ob- 35 serving the pictures ~~at~~ at a time.

5. In a telescope for submarine boats, the combination with a barrel, of a main objective system capable of producing a picture of a certain part of the horizon, subsidiary objective systems capable of producing 40 smaller subsidiary pictures of other parts of the horizon, all objective systems being adapted to project the pictures downwardly within the barrel, means for erecting the subsidiary pictures with respect to the main pic- 45 ture, intermediate lenses within the barrel, and an ocular system arranged for observing the pictures all at a time.

6. In a telescope for submarine boats, the combination with a barrel, of a main objective system capable of producing a picture of a certain part of the horizon, subsidiary objective systems capable of producing smaller subsidiary pictures of other parts of the horizon, all objective systems being 55 adapted to project the pictures downwardly within the barrel, means for erecting the subsidiary pictures with respect to the main picture, diaphragms within the barrel having apertures corresponding to the number, 60 place, and shape of the pictures, means for differently marking the subsidiary pictures, intermediate lenses within the barrel, and an ocular system arranged for observing the pictures all at a time.

7. In a telescope for submarine boats, the 65 combination with a vertically-disposed barrel, of a main objective system capable of collecting rays of light, and deflecting them downwardly within the barrel, a plurality of subsidiary objective systems smaller than 70 the main objective adapted to produce a similar effect with regard to other parts of the horizon, means for restraining part of the rays of light passing the main objective, so as to form recesses or dark places within the 75 circular field of view, in which places the subsidiary pictures are produced by the subsidiary objectives, a plurality of lenses within the barrel, and an ocular system in the lower part of the barrel. 80

8. In a telescope for submarine boats, the combination with a vertically-disposed barrel, of a main objective system capable of collecting rays of light of a certain part of the horizon, and deflecting them downwardly 85 within the barrel, a plurality of subsidiary objective systems smaller than the main objective, adapted to produce a similar effect with regard to other parts of the horizon, means for restraining part of the rays of light 90 passing the main objective, so as to darken those parts of the main picture at which the subsidiary pictures are produced, means for erecting the different pictures, a plurality of intermediate lenses within the barrel, and an 95 ocular system in the lower part of the barrel.

9. In a telescope for submarine boats, the combination with a vertically-disposed barrel, of a main objective system for a certain part of the horizon, disposed within the upper 100 part of the barrel, a plurality of subsidiary objective systems disposed below the main objective and directed to other parts of the horizon, all objectives being composed of lenses and a refracting-face adapted to collect rays of light and deflect them downwardly within the barrel, the subsidiary objectives producing pictures on a smaller scale than the main objective, means for erecting the subsidiary pictures, intermediate 105 lenses within the barrel, and an ocular system in the lower part of the barrel. 110

10. In a telescope for submarine boats, the combination with a vertically-disposed barrel, of lenses and a reflector at the upper end 115 of the barrel, for collecting rays of light from one direction and deflecting such rays downwardly within the barrel, a plurality of other lenses and reflectors, also at the upper end of the barrel, for collecting rays of light from other directions and deflecting these rays downwardly within the barrel, a diaphragm beneath the lenses and reflector first named, provided with an aperture, a plurality of parallel diaphragms corresponding with the 120 lenses and reflectors second named, each having apertures therein, a plurality of other lenses within the barrel, glass panes inter- 125

posed in the path of the several beams of light-rays and provided with means for marking the pictures, and an ocular and further lenses and a reflector at the lower end of the 5 barrel for deflecting the several beams of light rays.

11. In a telescope for submarine boats, the combination with a barrel, of a main system of lenses and a reflector at the upper end of the 10 barrel and arranged for collecting the rays of light from a part of the horizon and sending them downward through the barrel, a plurality of subsidiary systems of lenses and a reflector at the upper end of said barrel and arranged for collecting the rays of light from other parts of the horizon and sending them downward through the barrel, a diaphragm 15 beneath said main system and provided with an aperture, a plurality of parallel diaphragms for said plurality of subsidiary systems and each provided with apertures for the respective 20 system or systems in addition to the apertures in the preceding diaphragm, all the apertures in the last diaphragm corresponding to the main and the subsidiary fields of view within a circle, a plurality of lenses in 25 said barrel, and a system of lenses and a reflector with an ocular at the lower end of said barrel and arranged for deflecting the several 30 beams of rays and producing the chief and the subsidiary pictures.

12. In a telescope for submarine boats, the combination with a barrel, of a main objective for a part of the horizon at the upper end 35 of the barrel, a plurality of subsidiary objectives smaller than the main objective for other parts of the horizon at the upper end of said barrel, a main system of a reflector and lenses for said main objective and arranged 40 for sending the collected rays of light downward through said barrel, a plurality of subsidiary systems of smaller reflectors and lenses for said plurality of subsidiary objectives and arranged for sending the collected rays of light 45 separately downward through said barrel, a diaphragm beneath said main system and provided with an aperture, a plurality of parallel diaphragms for said plurality of subsidiary systems and each provided with apertures for 50 the respective system or systems in addition to the apertures in the preceding diaphragm, all the apertures in the last diaphragm corresponding to the main and the subsidiary fields of view respectively within a circle, the 55 main field of view having the full diameter of the circle and the subsidiary fields of view being disposed in the top part and if so preferred also in the bottom part of the area of the circle, a plurality of lenses in said barrel, 60 and a system of lenses and a reflector with an ocular at the lower end of said barrel and arranged for deflecting the several beams of rays and producing the chief and the subsidiary pictures, said reflectors and said lenses 65 being arranged for erecting all the pictures.

13. In a telescope for submarine boats, the combination with a barrel, of a main objective for the fore part of the horizon at the upper end of said barrel, a plurality of subsidiary objectives smaller than said main objective for other parts of the horizon at the upper end of said barrel, a main system of a reflector and lenses for said main objective and arranged for sending the collected rays of light downward through said barrel, a plurality of subsidiary systems of smaller reflectors and lenses for said plurality of subsidiary objectives and arranged for sending the collected rays of light separately downward through said barrel, a diaphragm beneath 70 said main system and provided with an aperture, a plurality of parallel diaphragms for said plurality of subsidiary systems and each provided with apertures for the respective system or systems in addition to the apertures in the preceding diaphragm, all the apertures in the last diaphragm corresponding to the main and the subsidiary fields of view respectively within a circle, the chief field of view having the full diameter of the circle 80 and the subsidiary fields of view being disposed in the top part and if so preferred also in the bottom part of the area of the circle, a plurality of lenses in said barrel, a system of lenses and a reflector with an ocular at the lower end of said barrel and arranged for deflecting the several beams of rays and producing the chief and the subsidiary pictures, and means for differently marking the subsidiary pictures. 85

14. In a telescope for submarine boats, the combination with an extensible barrel, of a main objective for a part of the horizon at the upper end of said extensible barrel, a plurality of subsidiary objectives smaller than said main objective for other parts of the horizon at the upper end of said extensible barrel, a main system of a reflector and lenses for said main objective and arranged 105 for sending the collected rays of light downward through said extensible barrel, a plurality of subsidiary systems of smaller reflectors and lenses for said plurality of subsidiary objectives and arranged for sending the collected rays of light separately downward 110 through said extensible barrel, a diaphragm beneath said main system and provided with an aperture, a plurality of parallel diaphragms for said plurality of subsidiary systems and each provided with apertures for the respective system or systems in addition to the apertures in the preceding diaphragm, all the apertures in the last diaphragm corresponding to the chief and the subsidiary fields of view respectively within a circle, the chief field of view having the full diameter of the circle 115 and the subsidiary fields of view being disposed in the top part and also in the bottom part of the area of the circle, a plurality of lenses in said extensible barrel, a system of 120 lenses and a reflector with an ocular at the lower end of said extensible barrel and arranged for deflecting the several beams of rays and producing the chief and the subsidiary pictures, said reflectors and said lenses 125 being arranged for erecting all the pictures. 130

6
lenses and a reflector at the lower end of said extensible barrel and arranged for deflecting the several beams of rays, an ocular arranged for producing the main and the subsidiary pictures, said reflectors and said lenses being arranged for erecting all the pictures, and means for differently marking the subsidiary pictures.

In testimony whereof we have signed to this specification our names in the presence of two subscribing witnesses.
